ELECTRIC DISCHARGE APPARATUS

Roy M. Smith, Bethlehem, Pa., assignor to The
Bryant Electric Company, Bridgeport, Conn.,
a corporation of Connecticut

Application May 29, 1943, Serial No. 488,995

12 Claims. (Cl. 315—97)

1

My invention relates generally to electric discharge apparatus in the form of starting and operating control circuits and apparatus for electric discharge devices such as fluorescent lamps and, more particularly, to a two-lamp circuit and ballast for controlling the operation of a pair of such devices from a common source of current where it is necessary or desirable that the control devices, such as the ballast and other control accessories, be located remote from the lamps as, for example, in a bridge or floor lamp.

Heretofore it has been the usual practice to operate two lamps from a single supply circuit by means of a two-lamp control circuit employing a single two-lamp ballast device and a separate starter compensator device in the form of a small auxiliary reactor connected in the starting circuit of the leading lamp. The leading lamp is the lamp which draws a leading current and is connected in the leading power factor portion of the circuit. The ballast device of this circuit comprises a pair of reactors, one for each lamp, a capacitor for the leading lamp and may also include a small autotransformer all enclosed in a metal housing or casing filled with a suitable insulating compound. This device is commonly known as a ballast and in connection with two-lamp circuits it is referred to as a two-lamp ballast.

A starting switch or relay is provided for each lamp for initiating the lamp discharge in a well known manner after the lamp electrodes have become properly heated and the starting compensator is connected in series circuit relation with the starting switch and the leading lamp between one terminal of each of its electrodes so that the compensator is connected in the lamp circuit only during the starting period when the starting switch is closed. The compensator is automatically disconnected and rendered ineffective in response to the opening of the starting switch to initiate the lamp discharge.

Since the starting switch for each lamp is usually mounted near the lamp, it will be apparent that if the starting compensator of this circuit is to be mounted remote from the lamp a pair of separate wiring leads is required. In the usual application of the two-lamp circuit, the number of wiring leads required to connect the lamps and the starting and control equipment is of little or no consequence. This is the reason that these devices are usually mounted in a lighting fixture where sufficient space is available and in close proximity to each other. However, when these circuits are applied

2

to bridge and floor lamps and other devices of a similar nature where it is desirable to conceal the control apparatus and mounting space therefor is at a minimum, it becomes highly desirable to reduce the number of leads to a minimum number and also reduce the number of control devices to only a single unit, if possible.

This, of course, is exclusive of the two small starting switches or relays which are usually mounted on or adjacent to one of the lamp holders associated with each lamp.

In order to obtain this result, it is necessary to provide a control device or ballast which shall be reliable and not become useless on account of the failure of some relatively unimportant and inexpensive part thereof requiring the replacement of the entire unit and also one which incorporates the starting compensator in such manner that it will function in the proper way and be connected in the lamp circuit during the starting period only.

The starting compensator referred to herein is in the form of a small auxiliary reactor comprising an iron core with an air gap and a winding thereon which is utilized to increase the preheating current of the leading lamp electrodes during the starting period only. Therefore, with respect to the operation of lamps of certain sizes, the starting compensator is an important element of the circuit and the circuit cannot be simplified with respect to reducing the number of wiring leads by simply omitting this element.

Accordingly it is an object of my invention to provide for obtaining the foregoing results by providing a two-lamp control circuit for electric discharge lamps wherein the starting compensator device is incorporated into the ballast.

Another object of my invention is to provide a ballast device for use in two-lamp control circuits which embody as a part thereof a starting compensator together with a suitable switch device for rendering the compensator ineffective after the lamp has started and during its normal operation.

A further object of my invention is to provide a two-lamp control circuit utilizing a minimum number of wiring leads between the lamps and the ballast device.

Another object of my invention is to provide a two-lamp control circuit which is particularly suitable for use with bridge and floor lamps and the like.

Referring to the single figure of the drawing which illustrates one embodiment of the invention in schematic form, the circuit there shown

comprises generally a pair of double-ended electric discharge lamps 10 and 11 having electrodes 12 and 13 and 14 and 15, respectively, which are operated from a suitable current source represented by conductors 16 and 17 by means of a single or common ballast device 18.

The ballast 18 comprises a pair of main reactors 19 and 21 or their equivalent in the form of two integral reactors, a transformer 22 and a capacitor 23 all enclosed in a suitable housing or casing 24 filled with insulating compound in accordance with the usual well-known practice. While the housing is not shown specifically, it is to be understood that all of the elements within the rectangle designated by the numeral 24 are a part of the unitary ballast.

In accordance with my invention, the ballast 18 also includes a starting compensator 25 connected in series-circuit relation with the reactor 19 and a condenser 26 in the circuit of the lamp 10 which is the leading lamp of the circuit through conductor 28 connected to one terminal 21 of electrode 13.

It is to be understood that in actual practice the terminals of the electrodes of the lamps are the contact pins which engage contact fingers in the lamp holders and that the circuit connections are made to the terminals of the lamp holders instead of directly to the electrode terminals as shown.

The reactor 21 is connected to the other lamp 11 through conductor 28 which is connected to one terminal 29 of electrode 15. Terminals 31 and 32 of the other electrodes 12 and 14, respectively, are connected through conductor 33 to the supply conductor 16. The other terminals 34 and 35 of lamp 10, and 36 and 37 of lamp 11, are connected together through suitable starting switches or relays 38 or 39, respectively, in a well-known manner to provide a preheating circuit for the electrodes of each lamp during the starting period and interrupt these circuits to initiate the lamp discharge.

The details of the starting switches 38 and 39 have not been shown as any well-known thermal switch or glow relay may be used for this purpose.

Since the starting compensator 25 is connected in series-circuit relation with the main reactor 19, it will function during the starting period, that is, when the starting switch 38 is closed in the same manner as though it were connected directly in series with the starting switch 38 between the electrode terminals 34 and 35. However, it will also be apparent that the compensator will be in the circuit of the lamp after the starting switch 38 has opened and the discharge of the lamp initiated.

In order to provide for rendering the compensator 25 ineffective during the normal operation of the lamp, a cutout switch 41 is also incorporated in the ballast for controlling the effectiveness of the starting compensator. This switch may take any desired form so long as it responds to the flow of starting current in the leading lamp circuit and in this instance is illustrated as a thermal switch having normally open contact members 42 and 43, the movable contact member 43 being actuated by a bimetal member 44 the temperature of which is controlled by a heating element 45 connected in the lamp circuit, as shown.

The contact members 42 and 43 of this switch are connected to shunt the starting compensator 25 when closed. Since the heating element 45 is in the circuit at all times, and thereby is subjected to the normal operating current as well

as the starting current of the lamp, it functions not only to effect closure of the switch contacts 42 and 43 but also to hold them closed during normal operation of the leading lamp 10.

Due to the fact that the cutout switch 41 is of the thermal type, it has sufficient time delay characteristics to permit the capacitor 25 to function during the starting period of the lamp and then cut it out of the lamp circuit after its functioning is no longer required. It will be apparent that the same result is accomplished by means of this arrangement as though the compensator 25 were disconnected by means of the opening operation of the starting switch 38.

While the starting compensator 25 has been shown as a separate element of the ballast, it will be apparent that it also may be integral with one of the main reactors 19 and 21. By integral, it is meant that the core structure of the compensator may be an integral part of the core structure of one of the main reactors.

In view of the foregoing, it will be apparent that by incorporating the starting compensator 25 in the ballast 18 and utilizing the cutout switch 41 to control its effectiveness, the two-lamp circuit has been simplified to the point where it is more suitable for use with floor lamps and the like as only three main wire leads, namely 26, 28 and 33, are required between the ballast 18 and the two lamps 10 and 11. Assuming that the compensator 25 was controlled in the usual manner by the starting switch 38 and mounted in the base of the floor lamp remote from the lamps 10 and 11, it is apparent that two additional wiring leads would be required to make the connection.

The use of the cutout switch 41 makes it possible to locate the compensator 25 in the ballast and utilize it as effectively as before. All of the advantages of the prior two-lamp circuit are retained by the use of an additional inexpensive cutout switch and the field of application of the two-lamp circuit broadened. Thus in the case of floor and bridge lamps, the ballast in the form of a single piece of equipment may include all the necessary control devices and may be mounted or located in the base of the floor lamp without the use of extra leads as would otherwise be required.

The use of a thermal cutout switch in the ballast is not objectionable as the heating element thereof is protected by the capacitor 23 in the event that the leading lamp burns out or fails and commences to function as a rectifier. The capacitor 23 prevents the flow of excess current such as would otherwise damage the heating element of the control switch. Therefore, the incorporation of the compensator 25 into the ballast is not disadvantageous from this standpoint and, therefore, there is little likelihood of having the cutout switch fail and rendering the entire ballast useless.

While only one specific embodiment of my invention has been shown and described, it is to be understood that other modifications may be made without departing from the principles of my invention.

I claim as my invention:

1. An electric circuit for starting and operating a plurality of electric discharge lamps having electrodes from a single current source comprising, circuit means for connecting said lamps in parallel to the source, a single reactor connected in series with one lamp, a plurality of reactors connected in series with another of the lamps, and current responsive switch means operable to shunt one of said series connected reactors from

its associated circuit in response to the flow of initial starting current to the lamp.

2. A starting and operating circuit for a plurality of electric-discharge lamps comprising, circuit means for connecting said lamps in parallel circuit relation to a common current source, a reactor connected in series circuit relation with each lamp, an auxiliary reactor and a capacitor connected in the circuit of one lamp, and a thermal switch connected to be responsive to the starting current of the said one lamp circuit operable to shunt the auxiliary reactor from said circuit by a delayed action following the initial energization of the circuit to start the lamp.

3. In combination, a pair of electric-discharge lamps, circuit means comprising a ballast device for connecting said lamps in parallel circuit relation to a current source, said ballast device including a pair of main reactors one for each lamp in each parallel circuit and an auxiliary reactor connected in series circuit relation with one of said main reactors, and current responsive means operable to render the auxiliary reactor ineffective within a predetermined time after the circuit means is energized to start the lamps and to maintain said auxiliary reactor ineffective during the normal operation of its associated lamp.

4. The combination with a source of electrical energy, of a pair of electric discharge lamps, circuit means connecting said lamps to the source in parallel circuit relation, reactance means connected in series circuit relation with one lamp, reactance means connected in series circuit relation with the other lamp, and switch means connected to be responsive to the flow of starting current through said other lamp for shunting a portion of the reactance means in series circuit relation therewith after said lamp has started.

5. The combination with a source of electrical energy, of a pair of electric discharge lamps, circuit means connecting said lamps to the source in parallel circuit relation, reactance means connected in series circuit relation with one lamp, reactance means connected in series circuit relation with the other lamp, and switch means having normally-open contact elements connected in shunt relation with a portion of the reactance means in series with said other lamp, and an operating element for said contact members connected to be responsive to the flow of starting current in the circuit of said other lamp, whereby said switch means functions to render the said portion of the reactance means ineffective after the lamp has started.

6. A starting and operating circuit for operating a pair of electric discharge lamps from a common source of electrical energy comprising, circuit means for connecting said lamps to the common source in parallel circuit relation, and a single ballast device interposed in the circuit means, said ballast including a main reactor connected to be in series with each lamp, an auxiliary reactor connected in series with one of the main reactors, and a current responsive shunting switch for said auxiliary reactor, said switch being connected to respond to the starting current of its associated lamp and operable to render the auxiliary reactor ineffective after the lamp has started.

7. The combination with a source of electrical energy, of a pair of electric discharge lamps connected in parallel circuit relation thereto, said devices having electrodes connected to be supplied with heating current, switch means connected

with each lamp to automatically control the heating current thereof, a first reactor connected in series circuit relation with one lamp, a second reactor and a capacitor connected in series circuit relation with the other lamp to cause said lamp to draw a leading current from the source, a third reactor connected intermediate the second reactor and its associated capacitor to function as a starting compensator for the leading lamp, and a thermal switch responsive to the starting current in the leading lamp circuit operable to shunt said third reactor following the initiation of the discharge of said leading lamp.

8. The combination with a source of alternating current, of a pair of gaseous electric-discharge lamps having electrodes at each end thereof adapted to be supplied with preheating current, circuit means connecting one electrode terminal of each lamp to one side of the source and another electrode terminal of each lamp to the other side of the source, a starting switch connected between the other terminals of the electrodes of each lamp for controlling the flow of preheating current through the electrodes and the starting of the lamps, and a common ballast interposed in the circuit between the lamps and one side of the source, said ballast including reactor means in series with one lamp, reactor means and capacitor means in series with the other lamp, whereby said lamps operate with lagging and leading currents respectively, and an auxiliary starting reactor incorporated in said ballast and connected in circuit relation with the capacitor and its associated reactor, and a thermal switch also incorporated in said ballast and having a heating element connected to be responsive to the current flowing in the leading lamp circuit operable to shunt said auxiliary starting reactor subsequent to the operation of the starting switches to render said auxiliary reactor ineffective during the normal operation of its associated lamp.

9. In electric discharge apparatus comprising, a pair of electric discharge devices connected to be operated in parallel from a source of alternating current supply and each having a pair of thermionic electrodes, a starting switch connecting each pair of electrodes in series to the source operable to control the heating of the electrodes and the starting of the devices, a first reactor connected in series with one of said devices, a second reactor and a capacitor connected in series with the other of said devices, said reactors and capacitor constituting a ballast for operating both lamps together from a common current source, a starting reactor forming a part of the ballast and being connected in series with the second reactor and capacitor, and switch means also forming a part of the ballast and operable to short circuit said starting reactor in response to the flow of a predetermined amount of current therethrough during the starting period of its associated lamp, thereby to render said starting reactor ineffective during the normal operation of the lamp.

10. A unitary ballast device for use in a two-lamp control circuit for electric discharge lamps and the like comprising, a pair of main reactors connected in parallel circuit relation and each disposed for connection, to a separate discharge lamp, an auxiliary reactor connected in series circuit relation with one of said main reactors, and switch means having contact members connected in shunt relation with the auxiliary reactor and an electroresponsive operating element connected to be energized in accordance with the current flow through the auxiliary reactor, there-

by to provide for shunting the auxiliary reactor from its associated parallel circuit in response to predetermined current flow therethrough.

11. A unitary ballast device for use in a two-lamp control circuit for electric discharge lamps and the like comprising, a pair of main reactors connected in parallel circuit relation and each disposed for connection to a separate lamp, an auxiliary reactor connected in series circuit relation with one of said main reactors, and thermal switch means operable to shunt the auxiliary reactor from its associated parallel circuit by a delayed action in response to the flow of a predetermined amount of current therethrough.

12. A unitary ballast device for use in a two-lamp control circuit for electric discharge lamps

comprising, a transformer, a pair of main reactors connected in parallel circuit relation with the transformer and each disposed for connection to a separate lamp circuit, a condenser and an auxiliary reactor connected in series circuit relation with only one of said main reactors, and a thermal switch having contact members connected in shunt relation with the auxiliary reactor and a heater element connected to be responsive to the current flow through the auxiliary reactor, thereby to provide for rendering said auxiliary reactor ineffective within a predetermined time after the parallel circuit in which it is connected is initially energized.

ROY M. SMITH.
